FLATIRON STAND

Edwin F. Peterson, Kewanee, Ill.

Application February 18, 1952, Serial No. 18,561

Term of patent 14 years

(Cl. D49—6)

To all whom it may concern:

Be it known that I, Edwin F. Peterson, a citizen of the United States, residing at Kewanee, in the county of Henry and State of Illinois, have invented a new, original, and ornamental Design for Flatiron Stand, of which the following is a specification, reference being had to the accompanying drawing, constituting a part hereof.

Fig. 1 is a top plan view of a flatiron stand, showing my new design;

Fig. 2 is an end elevational view thereof;

Fig. 3 is a transverse cross-sectional view thereof taken along the line 3—3 in Fig. 1.

I claim:

The ornamental design for a flatiron stand, substantially as shown.

EDWIN F. PETERSON.
